DRAFT, DUST, AND WEATHER EXCLUDER FOR HINGED DOORS AND WINDOWS

Filed Dec. 23, 1926

per

John Petrie INVENTOR.
A. D. Dryden, Attorney.

UNITED STATES PATENT OFFICE.

JOHN PETRIE, OF GLASGOW, SCOTLAND, ASSIGNOR TO DONALDSON MANUFACTURING COMPANY LIMITED, OF GLASGOW, SCOTLAND.

DRAFT, DUST, AND WEATHER EXCLUDER FOR HINGED DOORS AND WINDOWS.

Application filed December 23, 1926, Serial No. 156,662, and in Great Britain November 3, 1926.

This invention relates to draft, dust and weather excluders (hereinafter for brevity referred to simply as "draft-excluders") for hinged doors or windows (hereinafter referred to simply as "hinged members" for convenience of description) of the type comprising a draft-excluding member mounted on the sill below the hinged member and adapted to be turned upward into an operative position about one of its edges, which acts as a fulcrum, by means provided on the hinged member.

According to this invention the means on the hinged member for moving the draft-excluding member into its operative position is mounted on the free edge of the hinged member instead of on the hinged edge. In this way the draft-excluding member is lowered into its inoperative position immediately the hinged member begins to open and is moreover not raised into its operative position until the hinged member is nearly shut, which is particularly useful in its application to hinged members where the draft-excluding member might be otherwise damaged by being subjected to pressure by a moving object or a person's foot, when in its raised or partially raised position. The said means comprises a member so shaped as to engage under and gradually lift or lower the draft-excluding member as the hinged member closes or opens respectively. The two opposite edges of the said member may be both shaped in the manner specified so that it can be applied to either right hand or left hand hinged members.

In addition, a flat member adapted to be secured to the front of the hinged member and to project along the whole length thereof is provided, this member extending downwardly so as to overhang the draft-excluding member when the latter is in its operative position. This serves to prevent any rain or draft from passing behind the top of the draft-excluding member.

Referring to the drawings:—

Fig. 1 is a front view of a portion of the hinged member showing the excluder applied thereto.

Fig. 2 is a section on line II—II in Fig. 1. Fig. 3 is a fragmental plan view.

In the construction illustrated the draft-excluding member 1 consists of a long, flat metallic strip, which is folded over upon itself (see Fig. 2). Near its extremity, the

upper folded-over portion of said member (considered when the latter is in its inoperative or substantially horizontal position, shown in dotted lines in Fig. 2) is curved outward at 1^a away from the bottom portion 1^b of the member. This may be formed by rolling the strip to the required section. A long metallic strip, or plate 2, (hereinafter called "sill plate") is secured on the top of the sill of the hinged member, partly at the outside and partly below the latter, said sill plate being formed with upwardly projecting flanges 2^a and 2^b, the said sill plate being of channel shape.

The draft-excluding member is loosely arranged in the sill plate between the flanges thereof, the edge of the lower folded-over portion 1^b of said member bearing against the inside of the outermost flange 2^b on the sill plate and the curved part of the upper folded-over portion 1^a of said member extending around the edge of the outermost flange on the sill plate. The curvature of the part 1^a is such that it always maintains contact with the edge of the flange 2^b and when in its horizontal position, shown in dotted lines, it is just flush with the front of this sill plate. The edges of the draft-excluding member act as a loose hinge therefor.

The member (hereinafter referred to as "operating plate") provided on the hinged member 4 for moving the draft-excluding member into its operative position comprises a substantially rectangular plate 5 having apertures for screws 6 by which it is secured on the edge of the hinged member. This operating plate is provided at its lower front edge with an inwardly curved recess 5^a so shaped as to provide a sharp projection 5^b at the lower corner of the operating plate. Preferably this operating plate is provided with such recesses on opposite edges thereof (as shown in Fig. 2) so that it can be applied to left or right hand hinged members. The lower part of the hinged member is preferably cut away so that the plate is mounted in a counter-sunk position thereon and in a position in which it extends below the hinged member. The front plate 8 on the hinged member (hereinafter called a "berge plate") is flat and is also fixed by screws 9 to the front of the hinged member and extends across the whole width thereof.

In order to allow the operating member to

be raised into its operative position when the hinged member is nearly closed and lowered into its inoperative position immediately the hinged member begins to open, the 5 front lower edge of the hinged member must be cut away on a curve as indicated at 7, Figs. 1 and 2, for the whole width thereof. The berge plate 8 is adapted to extend below the cut away portion of the hinged member 10 so as to screen it and also to overhang the draft-excluding member when the latter is in its operative position.

The operating plate on the hinged member is as previously stated located upon the 15 free vertical edge thereof and projects downwardly below the hinged member, the sill plate and/or the sill being slotted or cut away at 10 so as to provide a passage for the operating plate.

20 When the hinged member is being closed, the operating plate thereon contacts with the innermost longitudinal edge of the draft-excluding member, turning the latter upward about the longitudinal edge of the bottom 25 folded-over portion of said draft-excluding member, said edge bearing against and hinging on the outermost flange of the sill member. When the hinged member is fully closed, the draft-excluding member is inclined thereto, and thus covers the aperture 30 between the bottom of the hinged member and the top of the sill. Moreover, when said draft-excluding member is being turned upward, the outwardly projecting part of 35 the upper folded-over portion thereof moves around the adjacent flange of the sill member, its inner face contacting with the top of said flange when the draft-excluding member is in its fully inclined, or operative, 40 position. Thus, in order to penetrate to the back of the draft-excluding member, drafts, dust and rain have first to pass the additional draft-excluding means formed by the 45 upper folded-over portion of the draft-excluding member. It will be obvious that the said curved part effectively screens the loose joint between the fulcrumed edge of the portion 1^b and the sill.

50 In addition, as the berge plate overhangs the upper edge of the excluding member, this will prevent drafts, dust and rain from passing between the upper edge of the draft-excluding member and the hinged member 55 and thereby serves as supplementary draft-excluding means.

In a modified construction, the sill member is made from a flat, metallic strip which is folded back upon itself to form the spaced, 60 upstanding flanges at the outermost longitudinal edge of the member. Two additional draft-excluding means are thus provided by this construction; one being formed by the contact of the inner face of said outwardly and forwardly projecting part on the 65

draft-excluding member with the innermost flange of the member on the sill, and the other by the contact of the longitudinal edge of said outwardly and forwardly projecting part and the inner face of the outermost 70 flange of the member on the sill.

My improved weather-excluding device is particularly easy to manufacture and fit. The member can be secured to any existing door sill by a few screws and it is then only 75 necessary to arrange the draft-excluding member loosely in said member. The device is also very efficient in action, owing to the provision thereby of one, or more supplementary draft-excluding means as described. 80

I claim:

1. An excluder for the purpose specified comprising at least one upstanding member on the sill; a strip folded over upon itself to form a draft-excluding member which is loosely arranged on the sill, one edge of said strip contacting with the upstanding member to serve as a fulcrum while the other edge is curved outwardly to engage around said upstanding member and an operating 85 plate adapted to be fixed to the free edge of the hinged member and having a curved recess in one edge which serves to raise and lower the draft-excluding member as the hinged member is opened and closed. 90

2. An excluder for the purpose specified comprising at least one upstanding member on the sill; a strip folded over upon itself to form a draft-excluding member which is loosely arranged on the sill, one edge of said strip contacting with the upstanding member to serve as a fulcrum while the other edge is curved outwardly to engage around said upstanding member; an operating plate adapted to be fixed to the free edge of the hinged member and having inwardly curved recesses in the opposite vertical edges, so that it can be applied to left hand and right hand hinged members, one of said recessed edges serving to raise and lower the draft-excluding member when the hinged member is opened and closed. 100

3. An excluder for the purpose specified, comprising at least one upstanding member on the sill; a strip folded over upon itself to form a draft-excluding member arranged on the sill, one edge of said strip contacting with the upstanding member to serve as a fulcrum while the other edge is curved outwardly to engage around said upstanding member and a berge plate adapted to be fixed to the front of the hinged member and to overlap the draft-excluding member when the latter is in its raised position. 105

4. An excluder for the purpose specified comprising at least one upstanding member on the sill, a draft-excluding member having a part which engages around the said upstanding member to act as a loose hinge, an operating plate adapted to be fixed to the 115 120 125 130

free edge of the hinged member and having inwardly curved recesses in its opposite vertical edges, so that it can be applied to left hand and right hand hinged members, one

5 of said recessed edges serving to raise and lower the draft-excluding member when the hinged member is opened and closed, and a

berge plate adapted to be fixed to the front of the hinged member and to overlap the draft-excluding member when the latter is 10 in its raised position.

In testimony whereof I affix my signature.

JOHN PETRIE.
